UNITED STATES PATENT OFFICE.

HARRY S. VINCENT, OF RIDGEWOOD, NEW JERSEY.

THROTTLE-VALVE.

1,227,097.

Specification of Letters Patent. Patented May 22, 1917.

Application filed December 8, 1916. Serial No. 135,872.

To all whom it may concern:

Be it known that I, HARRY S. VINCENT, of Ridgewood, in the county of Bergen and State of New Jersey, have invented a certain new and useful Improvement in Throttle-Valves, of which improvement the following is a specification.

My invention relates to throttle valves of the double puppet type, and its object is to provide a throttle valve of such type which will be of simple and inexpensive construction, and afford the advantages of capability of being balanced to any desired degree, of presenting a maximum area for delivery of steam with a minimum of obstruction of the surrounding dome, and of downwardly delivering the steam from both disks of the valve, thereby preventing interference of currents.

The improvement claimed is hereinafter fully set forth.

In the accompanying drawings: Figure 1 is a vertical section, on the line *z z* of Fig. 2, through the throttle valve dome of a locomotive boiler and through a throttle valve illustrating an application of my invention; Fig. 2, a plan or top view; and Fig. 3, a horizontal section, on the line *y y* of Fig. 1.

In the practice of my invention, referring descriptively to the specific embodiment thereof which is herein exemplified, I provide a stand pipe, 1, which is supported in the usual manner in a dome, A, of a steam boiler, and in which, a bowl shaped chamber, 1^a, is formed a short distance below its top. The stand pipe is, as in the ordinary constructions, open at its top, and the dry pipe, 2, through which steam is supplied to the cylinder or cylinders, is connected to a lateral nozzle, 1^b, at its bottom.

A balancing ring, 3, on the upper portion of the inner surface of which there is formed an inverted conical valve seat, 3^a, is fitted in the top of the stand pipe, 1, a steam tight joint being formed between its outer surface and the stand pipe, by grinding. Inasmuch as the balancing ring is continuously subjected to steam pressure acting to retain it in position, during the periods in which the boiler is under steam, it is not of importance that it should be positively connected to the stand pipe, except to the extent that it is advisable to prevent its undesired rotation therein when the appliance is in service. Any suitable

and preferred means of detachably connecting the balancing ring to the stand pipe may therefore be applied, and, in the instance shown, this consists of a plurality of 6^a clamps, 3^b, which abut on the top of the balancing ring, and are brought to proper bearing thereon by nuts, 3^c, engaging studs, 3^d, fixed in the top of the stand pipe. It will be obvious that peripheral clamping 65 lugs on the balancing ring would constitute the mechanical equivalent of clamps separate therefrom.

A valve stem, 4, extends through a pipe, 4^a, from the space below the stand pipe, 1, 7^a to and through the chamber, 1^a, thereof, said stem being adapted to be raised and lowered by connections to its lower end, in the ordinary manner. A double puppet throttle valve is secured upon the stem, 4, 7^b adjacent to its upper end, by a nut, 4^b, said valve comprising upper and lower bushing sections, 5, 5^a, secured together by bolts, 5^b, and nuts, 5^c. The valve sections are outwardly curved or flared at the upper and lower ends, respectively, of the sections, the extreme diameter of the lower section not exceeding that which will permit it to be inserted and withdrawn through the open 8^a upper end of the stand pipe, when the balancing ring is removed for that purpose. An inverted conical face, 5^d, adapted to fit the corresponding valve seat, 3^a, of the balancing ring, is formed on the periphery of the upper valve section, 5, and a conical face, 5^e, adapted to fit a corresponding valve face, 1^c, on the top of the chamber, 1^a, is formed on the inner surface of the lower valve section, 5^a, at the lower end thereof. 8^b

The upper end of the chamber, 1^a, is bored out to receive a disk, 6, which is fixed on the valve stem, 4, between a collar, 4^c, thereon, and the nut, 4^b, by which the valve sections are held in position.

In the operation of the appliance, the throttle valve is raised from, and brought to, its seats, to, respectively, admit steam to, and shut it off from, the dry pipe, 2, by appropriate movements of the valve stem, 4, 10^a and when unseated, the disk, 6, is coincidentally raised, said disk preventing the entrance of wet steam from the lower portion of the dome, and directing the current of steam passing through the valve into the 10^b opening exposed by the unseating of the lower valve section.

It will be seen that the stand pipe may be

made of the minimum diameter required for the admission of steam, and is devoid of lateral projections, thereby offering a minimum of obstruction of the dome; that by variation of the internal diameter of the balancing ring, the throttle valve may be balanced to any desired degree; and that steam is delivered, without interference of currents, from both sections of the valve.

10 I claim as my invention and desire to secure by Letters Patent:

1. The combination of an open topped stand pipe, a balancing ring fitted in the top opening thereof, and a double puppet throttle valve, having oppositely inclined faces which seat, respectively, on oppositely inclined faces, of approximately equal area, on the balancing ring and on a subjacent seat in the stand pipe.

20 2. The combination of an open topped stand pipe; a balancing ring fitted in the top opening thereof; a double puppet throttle valve seating on said balancing ring and on a subjacent seat in the stand pipe; and 25 means, including a disk connected to and

movable with said valve, to prevent inward upward access of steam to its lower seat.

3. The combination of an open topped standpipe, having an internal bowl shaped chamber; a double puppet throttle valve fitting seats at the tops of the stand pipe and chamber, respectively; a disk fitting said chamber; and a valve stem on which said valve and disk are secured.

4. The combination of an open topped stand pipe, having an internal bowl shaped chamber; a double puppet throttle valve comprising two abutting sections, the upper of which is adapted to seat at the top of the stand pipe and the lower at the top of the chamber; a disk fitting said chamber; a valve stem on which said valve and disk are secured; and an open ended pipe surrounding the valve stem and extending from the chamber to the exterior of the stand pipe. 45

HARRY S. VINCENT.
